UNITED STATES PATENT OFFICE.

PAUL SCHRÖDER, OF FRIEDRICHSHAFEN, GERMANY, ASSIGNOR TO LUFTSCHIFFBAU ZEPPELIN GESELLSCHAFT MIT BESCHRÄNKTER HAFTUNG, OF FRIEDRICHSHAFEN, BODENSEE, GERMANY.

AIRSHIP.

Application filed December 15, 1925, Serial No. 75,488, and in Germany December 30, 1924.

My invention relates to gas supported airships, and more especially to the supporting gas and a method of changing at will the lift of such airships while travelling.

It is a well known fact that airships travelling over long distances continuously become lighter because of the fuel consumption. Therefore it is necessary for the purpose of compensating lift and weight to reduce the lift by letting out some of the carrying gas, which may become a comparatively big quantity after long distances have been covered. Of course this method is very expensive as the lost quantity of gas will have to be re-inflated before a new trip of the airship.

According to my invention I am doing away with this drawback by inflating part of the airship with a gas which is dissolvable in water. Such a gas will be heavier than hydrogen or helium, but still it has to be considerably lighter than air so as to cause lift for the airship. Ammonia for example is such a gas.

While travelling, as soon as it seems suitable with regard to the continuously decreasing weight, part of the special gas may be dissolved in the ballast water of the ship thereby adequately reducing the lift. Also an arrangement may be provided for continually dissolving part of the gas so that the consumption of fuel may be compensated.

A further advantage of my invention is that the special gas may be used for extracting water from the exhaust of the motors driving the airship. It is known that the exhaust gases of the motors contain such an amount of water that its weight would be sufficient for the compensation of the fuel consumption.

By leading the special gas into the exhaust gases it will be possible to precipitate part of the water in which the gas will remain dissolved. In this way the desired weight compensation is further increased.

If by any circumstances it should become desirable again to increase the lift of the

airship, for example after a landing where the ship may have taken over new loads, this may be attained by simply warming the watery solution of the special gas thus causing the gas to separate from the water so that part of the ship may be re-inflated with this gas.

Having given a general description of my invention I now want to point it out more in detail referring to the drawing which represents an example embodying my invention.

The figure is a vertical longitudinal section through the middle portion of an airship. In the main gas space 1 a container 2 for the special gas is provided having a hose 3 leading to the water ballast container 4 situated in car 5. A branch 6 of said hose is connected to the exhaust 7. Leadings 3 and 6 are controlled by operated valves 8.

I do not want to limit myself to the example described or shown in the drawing, as many variations will occur to those skilled in the art.

What I claim is:

1. An airship comprising a gas bag containing ordinary lifting gas; a gas bag containing lifting gas dissolvable in water; a receptacle containing water; and means for bringing said second gas into contact with said water.

2. An airship comprising a gas bag containing ordinary lifting gas; a gas bag containing ammonia; a receptacle containing water; and means for bringing said ammonia into contact with said water.

3. Method for compensating differences in lift in an airship which consists in using a gas dissolvable in water besides the ordinary lifting gas, said first gas being used as a lifting gas or being dissolved in water, according as circumstances may require.

4. Method for compensating differences in lift in an airship which consists in using ammonia besides the ordinary lifting gas; said ammonia being also used as a lifting gas or being dissolved in water, according as circumstances may require.

5. Method for compensating differences in lift in an airship which consists in using a gas dissolvable in water besides the ordinary lifting gas; said first gas serving as a lifting gas, and as a means for extracting water from the exhaust gases of the motors in said airships.

6. Method for compensating differences in lift in an airship which consists in using ammonia besides the ordinary lifting gas; 10 said ammonia serving as a lifting gas and as a means for extracting water from the exhaust gases of the motors in said airship.

PAUL SCHRÖDER.
